Primary Examiner — Cynthia Ramirez(74) *Attorney, Agent, or Firm* — Hoang Steve Ngo(57) **CLAIM**

The ornamental design for a waste receptacle, as shown and described.

DESCRIPTION

FIG. 1 is a front, left side, top view of a waste receptacle showing my new design;

FIG. 2 is front, top perspective view thereof;

FIG. 3 is a front view, the rear view being a mirror image thereof;

FIG. 4 is a left side, the right side being a mirror image thereof;

FIG. 5 is a top view thereof;

FIG. 6 is a bottom view thereof; and,

FIG. 7 is another front, left, top perspective view thereof.

The broken lines in the figures are for the purpose of illustrating environment that form no part of the claimed design.
